HANDLE FOR LOCKERS AND THE LIKE

Dagfinn O. Amdal, Rockford, Ill., assignor to National Lock Company, Rockford, Ill., a corporation of Delaware

Application March 7, 1956, Serial No. 40,499

Term of patent 14 years

(Cl. D10—8)

Fig. 1 is a side elevational view of a handle for lockers and the like embodying my new design;

Fig. 2 is a front elevation thereof;

Fig. 3 is a rear elevation thereof;

Fig. 4 is a top plan view thereof;

Fig. 5 is a sectional view on the line 5—5 of Fig. 3; and Fig. 6 is a sectional view on the line 6—6 of Fig. 1.

The characteristic features of the handle reside in the portions shown in full lines.

I claim:

The ornamental design for a handle for lockers and the like, substantially as shown and described.
